BOOK END

Roger Engel, Brooklyn, N. Y., assignor to Gould Novelties, Inc., New York, N. Y.

Application March 28, 1949, Serial No. 1,663

Term of patent 7 years

(Cl. D33—3)

To all whom it may concern:

Be it known that I, Roger Engel, a citizen of the United States, residing at Brooklyn, in the county of Kings and State of New York, have invented a new, original, and ornamental Design for Book Ends, of which the following is a specification; reference being had to the accompanying drawing, forming a part thereof.

Fig. 1 is a front perspective view of book ends, showing my new design.

Fig. 2 is a rear perspective view of the same.

I claim:

The ornamental design for a book end, substantially as shown.

ROGER ENGEL.
